CLAIM

The ornamental design for a cover for mobile phone, as shown and described.

DESCRIPTION

FIG. 1 is a top, front perspective view of a cover for mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, rear perspective view thereof;

FIG. 9 is a bottom rear perspective view thereof; and,

FIG. 10 is a bottom front perspective view thereof depicting the cover for mobile phone in a standing configuration.

The dashed broken lines, and the unshaded regions bounded by the dashed broken lines, illustrate portions of the cover for mobile phone that form no part of the claimed design.

1 Claim, 8 Drawing Sheets
